UNITED STATES PATENT OFFICE.

JAMES B. SMALL, OF CHARLESTON, WEST VIRGINIA, ASSIGNOR TO THE LIBBEY-OWENS SHEET GLASS COMPANY, OF TOLEDO, OHIO, A CORPORATION OF OHIO.

LEER FOR CONTINUOUS SHEET GLASS.

Application filed July 14, 1924. Serial No. 725,851.

This invention relates to the art of making sheet glass, and more particularly to improvements in the leer in which the glass sheet is annealed.

5 In certain types of sheet glass producing apparatus, the sheet, which is made in the form of a continuous strip or ribbon, is carried slowly on a suitable conveyor through a long horizontal leer, in the form 10 of a substantially closed chamber or oven. Suitable heaters placed at intervals in this oven regulate the temperature at different positions from end to end thereof so that the sheet will be gradually cooled and tempered. Ordinarily the heating of the leer 15 is accomplished by a series of gas burners positioned at intervals along the lower portion of the chamber or oven. The tendency is for each burner to cause a localized hot 20 spot directly thereabove, and this does not give as uniformly controlled temperature conditions throughout the leer as might be desired.

According to the present invention each 25 burner, which is in the form of a gas pipe extending transversely across the lower portion of the leer and provided with a longitudinal series of feed openings for the gas, is provided with a sheet metal shield supported above and extending somewhat to either side of the burner. The heat from the burner must either be radiated from this 30 shield or must escape around the two sides of the shield, and in this way the heat will be diffused across a comparatively large area of the leer chamber above the burner, and thus avoid the spotty heat conditions heretofore present.

Other manifest advantages of this construction will be apparent from the following detailed description of one approved form of the apparatus.

In the accompanying drawings:

Fig. 1 is a longitudinal vertical section 45 through the hot end of the leer.

Fig. 2 is a similar section through the cool or discharge end of the leer.

Fig. 3 is a sectional perspective on an enlarged scale through a portion of the leer 50 and burners.

At 1 is indicated a portion of the drawing and flattening mechanism which draws the continuous sheet of glass 2 from the glass producing machine and feeds the glass 55 into the leer or annealing oven 3. The con-

veyor for carrying sheet 2 through the leer is here shown as a series of parallel horizontal driven rollers 4, usually formed of asbestos. These rollers are all driven at the same speed so as to slowly carry sheet 2 60 longitudinally through the leer. Leer 3 is in the form of a very long closed chamber, the walls being formed of suitable heat-retaining material.

At intervals throughout the lower portion 65 of the leer, beneath sheet 2, are positioned the improved burners or heaters constituting the particular subject-matter of this invention. Each burner comprises a horizontal gas pipe 5 extending transversely 70 across the lower portion of the leer, preferably parallel with the conveying rollers 4. This pipe 5 is provided with longitudinal rows of openings 6 in the upper portion thereof which supply the burner 75 flames. A pair of parallel pipe supports 7 are positioned one at either side of gas pipe 5, and bars 8 connecting these pipes at intervals serve as supports for the burner pipe 5. A sheet-metal shield 9, preferably 80 bowed or of an inverted V-shape as shown in the drawings, is supported on the pipes 7 above the burner pipe 5.

The flames from burner 5, are covered and partially enclosed by the shield 9, so 85 that the shield becomes highly heated and acts as a radiating plate which throws off its heat evenly across a rather large area of the upper portion of the leer. The heated gases from the burner flow up and 90 around the edges of the shield as shown at 10, Fig. 1, and also contribute in heating the annealing oven. It will be noted that the heat from a single burner instead of 95 being confined to an intense heat at one particular location is distributing more or less evenly over a comparatively large portion of the heating chamber.

The burners 5 are arranged at unequal intervals along the leer, being substantially 100 close together at the hotter end of the leer and spaced further apart as the cooler end of the leer is approached. As shown in Fig. 2, there are no burners throughout a considerable extent of the cool end of the leer, 105 the heating of this end being accomplished by convection currents from the hotter end of the leer and the heat radiating from the glass sheet itself.

This improved burner shield not only acts 110

to spread or diffuse the heat from the burner, but also protects the burner from falling glass, shields the glass sheet from a large portion of the carbon deposits that might result from the direct application of the heating flames, and also assures an easy and uniform combustion at the burners due to the feeding air currents that will be set up centrally beneath the cover shields. While the shield shown is of sheet metal, it could be built of clay or carborundum or other heat-resisting material.

Obviously, other forms of heating elements could be substituted, with like results, for the gas burners.

Claims:

1. In combination with a leer and a conveyor for carrying a continuous strip of glass therethrough, a plurality of heating elements positioned at spaced locations in the leer, and heat radiating and deflecting elements positioned between the heating elements and the sheet.

2. In combination with a leer and a conveyor for carrying a continuous strip of glass therethrough, a plurality of heating elements positioned at spaced locations in the leer, and a heat radiating and deflecting member positioned between each heating element and the sheet.

3. In combination with a leer and a conveyor for carrying a continuous strip of glass therethrough, a heater in the leer comprising a burner pipe provided with a series of gas openings which supply the flames, and a shield mounted between the flames and the glass sheet.

4. In combination with a leer and a conveyor for carrying a continuous strip of

glass therethrough, a heater in the leer comprising a burner pipe provided with a series of gas openings which supply the flames, and a metallic shield mounted between the flames and the glass sheet.

5. In combination with a leer and a conveyor for carrying a continuous strip of glass therethrough, a heater in the leer comprising a burner pipe provided with a series of gas openings which supply the flames, and a shield member mounted above and at the sides of the burner so as to radiate heat therefrom or deflect heated gases therearound, and diffuse the burner heat across a large area of the sheet.

6. In combination with a leer and a conveyor for carrying a continuous strip of glass therethrough, a series of burners positioned at intervals through the leer, and shielding means positioned between the burners and glass sheet.

7. In combination with a leer and a conveyor for carrying a continuous strip of glass therethrough, a series of burners positioned at intervals through the leer, and a series of shielding means arranged between the burners and glass sheet.

8. In combination with a leer and a conveyor for carrying a continuous strip of glass therethrough, a series of burners positioned at intervals through the leer, and a shield positioned between each burner and the glass sheet, so that heat must be radiated from the shields or be deflected between the shields before reaching the sheet.

Signed at Charleston, in the county of Kanawha, and State of West Virginia, this 1st day of July, 1924.

JAMES B. SMALL.
